Application December 2, 1954, Serial No. 472,632

6 Claims. (Cl. 122—149)

This invention relates to steam boilers, and more particularly to fire tube boilers adapted to burn gaseous or liquid fuels.

A general object of the invention is the provision of efficient steam boilers which have a high capacity for the generation of steam in comparison with their overall dimensions. Other objects include the provision of steam boilers in which localized overheating and deposits of boiler scale are prevented by forced circulation within the boiler and the use of finned tubes to increase heat transfer, the provision of boilers having radiant sections and convection sections in which the flue gases are cooled in the radiant sections to such an extent that there is less likelihood of damage to the fire tubes in the convection sections, and the provision of durable and reliable steam boilers which can be manufactured at reasonable cost.

Preferred forms of boilers embodying the invention are shown in the accompanying drawings, in which—

Figure 1 is a longitudinal section through one form of boiler embodying the invention.

Figure 2 is an end elevation of the boiler shown in Figure 1.

Figure 3 is a fragmentary transverse section taken as indicated by the line 3—3 of Figure 1.

Figure 4 is a fragmentary longitudinal section showing another form of boiler embodying the invention.

Figure 5 is a fragmentary transverse section taken along line 5—5 of Figure 4, and

Figure 6 is a fragmentary longitudinal section showing still another form of boiler embodying the invention.

As shown particularly in Figures 1, 2 and 3, a preferred form of boiler embodying our invention may comprise a shell 10, to the opposite ends of which are welded tube sheets 12 and 14. A large combustion tube 15 extends between and is welded to the tube sheets. At the front of the boiler, end portion 16 of tube 15 projects beyond the tube sheet 12 and acts as a support for any convenient form of burner, such as the gas burner 18; the burner may be supplied with air by means of a blower 19. Combustion of the fuel takes place within the combustion tube 15, the hot products of combustion traveling in the direction indicated by the arrows in Figure 1.

In order to increase the efficiency of heat transfer in the combustion tube, which constitutes the radiant section of the boiler, the tube is provided with external, longitudinally extending fins 20 which extend for the greater portion of the length of the tube 15 between the headers 12 and 14. Fins 20 are preferably welded to the exterior of the tube 15 in the manner disclosed in the prior patent of John W. Brown, Jr., No. 2,261,137, issued November 4, 1941. Finned tubes made according to the aforesaid patent have excellent heat exchange characteristics because of the nature of the paths for flow of heat between the tube and the fins.

Combustion gases discharged from the rear end 22 of the tube 15 flow into the rear housing member 23

which is bolted as at 25 to a flange 26 welded to the tube sheet 14. Housing member 23 is preferably lined with a refractory material 27, as shown. The hot combustion gases discharged into housing 23 are reversed in direction and flow toward the front or stack end of the boiler through the fire tubes 30 which extend between the tube sheets 12 and 14 and are rolled into the tube sheets in the usual manner. In order to increase the efficiency of heat transfer between the flue gases and the fire tubes 30, the tubes are preferably provided with internal fins 31; internally finned tubes such as shown in the pending application of Gaddis, Myers and Welsh, Serial No. 185,418, filed September 18, 1950, now Patent No. 2,731,709, and owned by the assignee of the present application, are satisfactory.

From the fire tubes 30 the combustion gases are discharged into a front housing 33; the upper surface of the housing, as shown particularly in Figure 2, is a flat plate 34 to which the flue connection 35 is secured. Housing 33 is preferably lined with refractory material 36 and is bolted as at 37 to a flange 38 welded to the tube sheet 12.

The boiler is provided with the usual gauges and controls, steam is discharged from the boiler through the outlet 40, and feed water is supplied thereto by means of a feed water pump 41 connected to the supply conduit 42. A blowdown connection 44 is provided at the bottom of the shell 10, and the entire shell is enclosed in a sheath 45 with insulating material 46 disposed between the shell and the sheath. The boiler is mounted on the supporting structure indicated in general at 47; this may be of any convenient design and construction.

In order to increase the rate of heat transfer in the radiant section constituted by the externally finned combustion tube 15, circulation is constantly maintained in the boiler by means of a circulating pump 48 which draws water in from the upper portion of the boiler through the flared end 49 of conduit 50 and discharges it through the open end 51 of conduit 52 within the interior shroud or tube 54. Shroud 54 surrounds the fins on the exterior of tube 15 and is provided with a flange 55 which is secured as by welding to the inner surface of the tube sheet 12. The opposite end 56 of shroud 54 extends near to, but is spaced from the tube sheet 14, leaving a space 57 as shown in Figure 1. In addition to the support given by flange 55, the shroud is supported and centered with respect to the finned tube 15 by studs 58 welded to the interior of the shroud and engaging the exterior of the tube.

In operation, feed water delivered to the boiler by the feed water pump 41 is discharged into the boiler through the end 51 of tube 52 into the interior of shroud 54. Also, additional water drawn from the upper portion of the boiler through conduit 50 is discharged by pump 48 into the same region. The water so pumped into the space between the exterior of the combustion tube 15 and the interior of the shroud 54 distributes itself annularly around the tube 15 in the space 60 before the beginning of the fins 20, and then flows longitudinally along the fins 20 within the shroud 54 and is discharged through the annular space 57 adjacent the tube sheet 14. Because of the extended surface area provided by the fins 20 and because of the flow of water along the fins, heat is extracted rapidly from the tube 15 and the tube is maintained at a temperature considerably below the temperature that would obtain if the tube did not have external fins and if there were no forced circulation of water.

Important advantages flow from the reduction in temperature of the combustion tube 15; the tube is enabled to extract more heat from the combustion gases flowing through it; corrosion and damage of the tube by the

combustion gases is reduced; the circulation prevents the occurrence of localized hot spots, and the deposition of solids on the external surface of the tube under ordinary operating conditions is substantially eliminated. For these reasons, the tube is less likely to burn out, and the efficiency of the tube is maintained for long periods of time. Large amounts of heat are removed from the combustion gases in the radiant section without requiring the radiant section to be of undue length, and the gases are discharged at reasonable temperatures into the housing 23. The gases then flow back from the housing 23 through the fire tubes 30, and here the internal fins 31 provide extended surface area, which results in efficient heat interchange between the flue gases and tubes so that a comparatively small number of relatively short fire tubes can extract sufficient heat from the flue gases to bring them down to the desired discharge temperature.

The circulation of the water within the boiler has a further important advantage at the inner surface of the tube sheet 14. The water discharged from the shell 54 impinges against this surface and constantly washes it, thereby preventing liming at this point. The circulation of water in combination with the reduced temperature of discharge of the combustion gases from the radiant section of the combustion tube 15 thus act together to prevent liming of the boiler and burning out of the fire tubes 30.

In the modified forms of the invention shown in Figures 4, 5 and 6, the boiler is constructed generally the same as the boiler shown in Figures 1, 2 and 3 and parts that are identical with parts shown in Figures 1, 2 and 3 have been given the same reference characters.

In the form of the invention shown in Figures 4 and 5, the shroud 61 is spaced from the front tube sheet 12, as indicated at 62, and is spaced from the rear tube sheet 14, as indicated at 63. The front end of the shroud is preferably flared slightly, as shown at 64, and the shroud is supported on and centered with respect to the combustion tube 15 by means of studs 65. At the rear end of the shroud, projections 67 engage the inner surface of the tube sheet 14 to locate the shroud longitudinally with respect to the combustion tube 15.

In order to provide for circulation through the shroud and on the exterior of the finned tube 15, conduit 52, which, as shown in Figure 1, receives the discharge from the circulating pump 48, is connected to a ring or manifold 68 which surrounds the combustion tube 15 in the space 62. Manifold 68 is provided with a series of discharge nozzles 69 which project slightly within the flared end 64 of the shroud 61 and are arranged to discharge streams of water into the interior of the shroud toward the rear of the boiler. The discharge of water in this zone creates circulation in excess of the volume of water discharged by the nozzles because of the injector effect which causes water to be drawn from the main body of water in the boiler into the flared end of the shroud. The operation of this form of the invention is essentially the same as that previously described, except that this arrangement provides additional circulation of water along the interior surface of the front tube sheet 12.

Figure 6 shows a further modification of the structure of circulating water over the exterior of the combustion tube 15. In this form of the invention the shroud 71 preferably consists of a cylindrical tube spaced from both tube sheets 12 and 14 as indicated at 72 and 73. The shroud is centered and supported on the tube 15 by studs 75 and is positioned longitudinally by extensions 76 and 77 which engage the inner surfaces of the tube sheets 12 and 14, respectively.

In this form of the invention the discharge from the circulating pump 48 through the pipe 52 is conveyed by conduit 53 to the center of the shroud 71, so that the circulating water is discharged centrally of the shroud and of the tube 15. The water flows in both directions from the point of discharge to the opposite ends of the

shroud, continuing out into the boiler proper through the spaces 72 and 73. The finned members 20a on the exterior of tube 15 do not extend through the central portion 78 of the combustion tube 15, so that the central portion 78 acts as a distribution zone in which the water discharged from the pipe 53 can flow annularly around the tube 15 and distribute itself along the channels provided by the fins. In this form of the invention there is forced circulation to the front of the boiler as well as to the rear, and water is circulated along the interior surfaces of both tube sheets 12 and 14. Also, in this form of the invention, the circulation of the water along the front half of the combustion tube 15 is counter to the flow of combustion gases therein.

15 In all of the forms of the invention the forced circulation of the water and the finned combustion tube prevent the combustion tube from reaching excessive temperatures, enable the combustion tube to abstract large quantities of heat from the gases passing therethrough, and 20 thus make the combustion tube into an extremely efficient radiant heat transfer section. Because of this construction, boilers embodying the invention have high capacity for their size, are durable and reliable because of the elimination of difficulties due to deposition of 25 solids and to corrosion of the fire tubes, and are efficient in their utilization of fuel.

Various changes and modifications can be made in the invention without departing from the spirit and scope thereof. The essential characteristics of the invention are 30 defined in the appended claims.

We claim:

1. A fire tube boiler comprising a shell, a front tube sheet and a rear tube sheet secured to said shell, a combustion tube extending through said shell in the lower portion thereof and secured to said tube sheets, a plurality of fire tubes extending between said tube sheets within said shell, a housing at the rear end of said shell adapted to direct products of combustion from said combustion tube into the rear ends of said fire tubes, a shroud within said shell and surrounding said combustion tube, said shroud extending for the major portion of the length of the combustion tube and having an open end whereby the interior of said shroud is in direct open communication with the interior of said shell at said open end of the shroud and immediately adjacent one of said tube sheets, and a pump for continuously circulating water primarily longitudinally along said combustion tube within said shroud and discharging at least part of said circulated water at said open end of said shroud into the main body of fluid within the shell immediately adjacent and in a direction toward said last mentioned tube sheet.

2. A boiler according to claim 1 wherein the water discharged by the pump is withdrawn from said boiler at 55 a level above said combustion tube and is discharged into said shroud adjacent the end thereof opposite the said open end thereof.

3. A boiler according to claim 1 wherein the other end of said shroud is also open and in open communication with the main body of water within said shell, and wherein said pump delivers water to a series of nozzles disposed around said combustion tube adjacent one end thereof and directed to the space between said shroud and said combustion tube and toward the opposite end of said combustion tube.

4. A boiler according to claim 1 wherein the pump discharges water into the central portion of said shroud, the water being discharged therefrom at both ends thereof.

70 5. A fire tube boiler comprising a shell, a front tube sheet and a rear tube sheet secured to said shell, a combustion tube extending through said shell in the lower portion thereof and being secured to said tube sheets, the major portion of the length of the exterior only of said combustion tube between said tube sheets being

provided with longitudinally extending horizontal fins, a plurality of fire tubes extending between said tube sheets within said shell, a housing at the rear end of said shell adapted to direct products of combustion from said combustion tube into the rear ends of said fire tubes, a shroud within said shell and surrounding said combustion tube, said shroud extending for the major portion of the length of the combustion tube and stopping short of one of said tube sheets to provide a discharge opening providing direct communication between the interior of said shroud and the interior of said shell at one end of the shroud and adjacent said last mentioned tube sheets, and a pump for continuously circulating water primarily longitudinally along said combustion tube within said shroud and discharging at least part of said circulated water through said discharge opening adjacent and in a direction toward said last mentioned tube sheet.

6. A fire tube boiler comprising a generally cylindrical horizontal shell, a front tube sheet and a rear tube sheet secured to said shell, a combustion tube extending horizontally through said shell in the lower portion thereof, said combustion tube being secured to said tube sheets and projecting beyond said front tube sheet, the major portion of the exterior only of the length of said combustion tube between said tube sheets being provided with longitudinally extending fins, a burner mounted on the projecting portion of said combustion tube and adapted to discharge hot products of combustion into said combustion tube, a plurality of internally finned fire tubes extending between said tube sheets within said shell, a housing at the rear end of said shell adapted to direct products of combustion from said combustion tube into the rear ends of said fire tubes, a housing at the

10
